UNITED STATES PATENT OFFICE.

JOHN E. HUMMON, OF DENVER, COLORADO.

DESIGN FOR A MARTIN LUTHER MEMORIAL BADGE, PIN, OR BUTTON.

48,974.

Specification for Design.

Patented May 2, 1916.

Application filed January 27, 1916. Serial No. 74,713. Term of patent 3½ years.

To all whom it may concern:

Be it known that I, JOHN E. HUMMON, a citizen of the United States, residing at No. 1620 East Sixteenth avenue, in the city and county of Denver and State of Colorado, have invented a new and original ornamental Design for a Martin Luther Memorial Badge, Pin, or Button, of which the following is a specification, reference being had to the accompanying drawing, forming part thereof.

The figure is a plan view of a badge, pin or button, showing my new design.

I claim:

The ornamental design for a Martin Luther memorial badge, pin or button, as shown.

JOHN E. HUMMON.

Witnesses:

F. P. WHITE,
L. O. WAVLE.
